UNITED STATES PATENT OFFICE.

ISAAC B. KELLER, OF PHILADELPHIA, PENNSYLVANIA, ASSIGNOR OF ONE-HALF TO
GEORGE C. FRANKLIN, OF PHILADELPHIA, PENNSYLVANIA.

LOCKING DEVICE FOR BOXES AND CONTAINERS.

1,157,942.

Specification of Letters Patent.

Patented Oct. 26, 1915.

Application filed July 30, 1915. Serial No. 42,825.

To all whom it may concern:

Be it known that I, ISAAC B. KELLER, a citizen of the United States, residing at Philadelphia, in the county of Philadelphia and State of Pennsylvania, have invented certain new and useful Improvements in Locking Devices for Boxes and Containers, and do hereby declare that the following is a full, clear, and exact description of the same, reference being had to the annexed drawings, making a part of this specification, and to the letters and figures of reference marked thereon.

My invention relates to boxes or containers and my object generally stated is to provide a securing device which will have the important advantages of simplicity in construction and manipulation and the absence of strings or loose parts and to this end my invention consists in the box locking means having the construction substantially as hereinafter specified and claimed.

The embodiment of my invention is illustrated in the accompanying drawings as applied to a box made of pasteboard or paper, comprising two telescopic members one constituting the container element and the other the cover element, and in such drawing—Figure 1 is a perspective view of such embodiment of my invention with the box parts closed and locked. Fig. 2 is a vertical section with the parts in the position shown in Fig. 1. Fig. 3 is a perspective view showing the box parts separated.

As already indicated, the box shown in the drawings comprises an inner receptacle member 10, and an outer closure member 11, the one fitting within the other with a loose fit so that they may be readily telescoped in opening and closing. Preferably but not necessarily the end and side walls are of substantially the same dimensions so that the inner member is contained completely within the outer member and to facilitate their separation the side walls of the outer member have each a cut-away portion or notch 13, that exposes the sides of the inner member 10, for the convenient grasp of the thumb and finger.

The locking device comprises a strip 14, which may be of heavy paper or card-board adapted to be inserted between the walls of the inner and outer box members and a strip or band 15, attached to and extending from one end thereof to the opposite end or side

of the outer box member 11, to which it is secured, and constitutes a flexible connection between the outer box member and said strip so that when the strip is thrust in between the walls of the two box members 60 said connection will extend across the wall of the inner box member 10, which is uncovered by the outer closure member. It must be seen that any outward tendency of the inner box member or tendency of the 65 two box members to separate will result in an outward pressure being applied to the strip or band 15, the effect of which is to place such band under tension that acts to pull the locking strip 15, against the side 70 of the inner box member and thus to increase the friction thereon with the result that a firm lock is produced, the grip of the lock strip being, in fact, increased by the tendency of the two box parts to separate. 75 Yet the removal of the locking strip 13, is easily and quickly accomplished merely by pulling directly upon it which may be conveniently done by the provision of a 80 tab 16, of some flexible material adapted to project sufficiently beyond the outer end of the strip as to enable it to be readily caught between the thumb and finger; and the matter of inserting the locking strip is obviously very simple and can be done very expeditiously. It is important that the locking strip 15, be of some flexible material, such as heavy paper or pasteboard to facilitate its insertion and removal because, 85 in these acts there is a turning movement 90 of the connecting band or strip 14, on its point of connection with the outer box member 11, which causes the point of the connection of said connecting band with the locking strip to move in a circle to which 95 the space between the end walls of the two box parts is tangent and hence, the locking strip must be capable of conforming more or less to the curvature of the arc thus described. To secure the best results the 100 length of the free portion of the connecting band 14, is the distance between the side of the box to which it is attached and the opposite side where the locking strip is inserted so that when the locking strip is inserted in a locked position the said connecting band will be fairly taut. In manufacturing the device the connecting band 14, is first attached to the locking strip then 105 the two box parts are placed together, the 110

locking strip is inserted between the end walls and then the connecting band is stretched across the outer wall of the inner member to the desired tightness and lapped over and secured to the proper wall of the closure member 11.

The connecting band 14, may be made of linen or paper and when so made it is lapped over and glued to the parts with which it is 10 to be connected and the tab 16, for the removal of the locking strip, may also be made of linen or other suitable material, and when so made is in the form of a strip as shown in the drawings, that extends to the 15 bottom and top of the locking strip 15, and at the free end of the latter is folded around and pasted or glued thereto so as to make a strong connection therewith. Of course the flexible connection 15, and tab 16, may be 20 otherwise made and made of other material and in such respects and in regard to other matters of detail, although I prefer the construction shown, I desire to have it understood that variation may be made without departing from the scope of my invention. The tab 16, being of flexible material, of course bends or folds down out of the way.

My invention is of special value in the parcel post service in that a minimum of 30 time and work is required in opening the container and again closing and securing the parts together.

Having thus described my invention what I claim is:—

35 1. A box comprising container and closure members with overlapping walls, one of said members having an exposed wall extending from one of its overlapped walls to its opposite overlapped wall and having a locking device consisting of a member insertible between and removable from said overlapping walls free from both of said walls and a connection between said device and one of the 40 box members that reaches from said locking member across said exposed wall of the box member.

50 2. A box comprising container and closure members with overlapping walls, one of said members having an exposed wall extending from one of its overlapping walls to its opposite overlapped wall and having a locking device consisting of a strip insertible between said overlapping walls and removable therefrom, said strip being free from both 55 of the walls between which it is insertible

and a connection between said strip and a wall of the closure member opposite said overlapping walls between which said strip is insertible and removable and extending across said exposed wall.

60 3. A box comprising container and closure members with overlapping walls, one of said members having an exposed wall extending from one of its overlapped walls to its opposite overlapped wall and having a locking device 65 consisting of a strip insertible between said overlapping walls and removable therefrom, said strip being free from both of the walls between which it is insertible and a connection between said strip and a wall of the closure member opposite said overlapping walls, between which said strip is insertible and removable and extending across 70 said exposed wall and a tab attached to said locking member.

75 4. A box comprising container and closure members with overlapping walls, having a locking device consisting of a flexible strip insertible between said overlapping walls and removable therefrom, said strip being free from both of the walls between which it is insertible and a connection between said flexible strip and a wall of the closure member opposite said overlapping walls, between which said strip is insertible and removable 80 and extending across said exposed wall and a tab attached to said locking member.

85 5. A box comprising telescopic members one of which incloses the other except at one side, having a locking means consisting of a strip of flexible material insertible between contiguous walls of said members and removable therefrom and a band attached to said strip and extending over the exposed portion of the inner box member and attached to the wall of the outer box member opposite the place of insertion of said strip.

90 6. A box comprising a member having an open side that gives access to its interior, and a member to cover such open side, the box 95 having double, closely spaced walls, at one side of said open side, means for preventing the removal of said cover member comprising a strip removably fitting the space between said walls, and a band connected therewith that reaches across said cover member from the strip to an opposite wall of the box and attached to the latter.

In testimony whereof I affix my signature.
ISAAC B. KELLER.
